ZERO PHASE SHIFT FILTER

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

In many electronic applications where filters are utilized an objectionable shift in phase occurs when the input signal passes therethrough. If the phase of the signal conveys a part or all of the data, the filter output may not be truly representative of the information being conveyed.

One approach to the problem has been to employ a tracking filter, which ties the phase of the output signal to that of the input signal by following the latter as it varies over the passband. However, not only are such tracking filters of complex design, but their cost is often prohibitive and in addition the possibility of a malfunction can not always be tolerated.

Another expedient has been to employ linear filtering techniques, two filters having phase variations in opposite sense being connected in series in an attempt to compensate for the overall phase shift. However, it is found that the slope of the characteristic curve increases with decreasing bandwidth, so that variations in phase cannot be overcome without adversely affecting the selective properties of the filter itself.

SUMMARY OF THE INVENTION

The present concept combines a lead network with an integrator to form a lag-free filter especially suitable for incorporation into a servoloop in order to extend the corner frequency of a servomotor while retaining a high gain at the low end of the passband. A feature of the concept resides in the attainment of controllable gain over a wide frequency range without introducing the instability and/or high noise conventionally associated with such control. An essential factor in the invention operation is the dynamic bounding of the output data as a continuous function of the input data.

OBJECTS OF THE INVENTION

One object of the present invention, therefore, is to provide a filter having essentially zero phase shift over a wide frequency range.

Another object of the invention is to provide a zero phase shift filter made up of a lead network and an integrator, the lead network acting as a dynamically bounded differentiator.

A further object of the invention is to provide a lag-free wide-band filter especially suitable for incorporation into a servoloop without introducing instability or raising the noise level of the system.

Other objects, advantages, and novel features of the invention will become apparent from the following detailed description of the invention when considered in conjunction with the accompanying drawings.

SHORT DESCRIPTION OF THE DRAWINGS

FIG. 1 is a block diagram of a type in which the present concept finds particular application;

FIG. 2 is a schematic circuit diagram of one form of zero phase shift filter designed in accordance with a preferred embodiment of the present invention; and

FIG. 3 is a modification of one portion of the circuit of FIG. 2.

DESCRIPTION OF THE PREFERRED EMBODIMENT

Although capable of incorporation into a large number of electronic filtering applications, such for example as those found in data processors, analog simulators and computing networks, a filter designed according to the principles of the present invention is particularly suitable for employment in a feedback circuit to control the operation of a servomechanism

by providing controllable gain over a wide dynamic range, by increasing stability of operation, and by reducing the followup error. Accordingly, the concept will be described in connection with such a servosystem, one type of which is illustrated in FIG. 1 of the drawings, although obviously the invention principles are not in any way limited to the particular arrangement selected as exemplary.

The standard feedback network of FIG. 1 includes a servomotor 10 driving a load 12, the motor 10 receiving an input signal through an amplifier 14. A portion of the motor output is fed back to the input of amplifier 14 through a filter 16, the amplitude of the feedback energy being controlled by some means such as a potentiometer 18. In conventional networks of this type, the filter 16 introduces an objectionable phase shift into the feedback signal passing therethrough, and it is a principal object of the present invention to improve system response by eliminating this objectionable shift in signal phase.

Conventional filters frequently utilized in electronic applications include the Bessel, Butterworth, Tchebyscheff, transversal, predictor and tapped delay line types. All of these possess inherent phase shift with frequency change. Three-pole Bessel filters are generally considered to have superior minimization of such phase shift—minus 67.5° at one octave above f_c .

Referring now to FIG. 2 of the drawings, it will be recognized that the particular embodiment of the present invention there illustrated is made up of two sections—a lead network 20 and an integrator 22. The concept is based upon the principle that, for the lead network 20,

$$E_{o1} = E'$$

where

$$E_{o1} = \text{output of network 20}$$

$$E_i = \text{input to filter}$$

and

$$|E'| \leq |E_i|$$

For the complete filter of Fig. 2

$$E_{o2} = \int_0^T (E') \frac{de}{dt}$$

where

$$E_{o2} = \text{output of the filter}$$

$$E' = f(E_i)$$

$$e = f(E')$$

$$|E'| \leq |E_i|$$

The essence of the present concept as exemplified by the circuit of FIG. 2 is an ability to perform the operation

$$E_o = E_i'$$

where

$$|E_o| \leq |E_i'|$$

This operation provides an approximate phase lead of 90°, and by dynamic bounding (to be discussed hereinafter) assures that the data-level-out will never exceed the data-level-in.

Classical active-element differentiators have the following gain vs. frequency relationship:

$$-e = T_p e_i$$

Such a differentiator, followed by an integrator with the typical gain vs. frequency relationship of

$$-e = \frac{1}{T_p} e_i$$

results in an overall gain vs. frequency relationship of

$$+e = T_p (1/T_p) = e_i$$

Thus, in using the classical differentiator with a classical integrator, no filtering (that is, amplitude attenuation as a function of data frequency changes) occurs.

When using the network of FIG. 2, however, the following relationship holds:

$$-e = (e_i)(1/T_p)$$

and the filter approximates the performance of a true integrator *without* the normal resultant phase lag. This results from the principle of dynamic bounding of the output signal.

Considering now the details of the lead network 20 of FIG. 2, it will be apparent that three parallel paths are provided for the input signal E_i . One path includes an operational amplifier A_1 in series with resistor R_1 , this combination being further in series with capacitor C_1 , resistor R_7 , and a further amplifier A_4 . A resistor R_2 shunts amplifier A_1 , and a capacitor C_2 shunts amplifier A_4 . Two diode-resistor combinations R_8-D_3 and $R_{10}-D_4$ are connected in parallel both with each other and with amplifier A_4 , as shown. The output terminal at which voltage E_{o1} appears is between resistors R_8 and R_{10} .

A second signal path includes an operational amplifier A_2 in series with resistors R_3 and R_6 . Shunting amplifier A_2 is the parallel combination of resistor R_4 and diode D_1 . Similarly, a third signal path includes operational amplifier A_3 in series with resistors R_5 and R_{11} , the parallel combination of resistor R_6 and diode D_2 shunting amplifier A_3 as brought out in the drawing.

In operation, a signal e_i applied to the input terminal flows through three paths respectively headed by resistors R_1 , R_3 and R_5 . Amplifiers A_2 and A_3 are half-wave rectifiers with precision gain characteristics. A_1 is an inverting amplifier. The respective outputs of A_2 and A_3 provide voltage levels for the *dynamic bounding* of the output data at E_{o1} .

C_1 , D_3 , D_4 and A_4 form a differentiator. The output of A_4 is continuously limited by A_2 , R_8 , R_9 and D_3 , as well as by A_3 , R_{11} , R_{10} and D_4 , so that

$$|E_{o1}| \leq |E_i|$$

on a dynamic basis.

The integrator 22 of FIG. 2 comprises the series combination of a resistor R_{12} and an amplifier A_5 , the latter being shunted by capacitor C_3 . The output of the complete filter appears at E_{o2} , as illustrated.

The following exemplary values for the components of FIG. 2 have been found to be satisfactory in practice:

$R_1, R_2, R_{12}=1$ megohm

$R_3, R_4, R_5, R_6=100$ kilohm

$R_7=120$ ohm

$R_8, R_9, R_{10}, R_{11}=1$ kilohm

$C_1=1$ μ fd.

$C_2=0.003$ μ fd.

$C_3=0.075$ μ fd.

$A_1, A_2, A_3, A_4, A_5=$ operational amplifiers

$D_1, D_2, D_3, D_4=$ diodes

When components having these values are employed in the circuit of FIG. 2, a sine wave input e_i produces an insertion loss of -3 db. at 0.175 Hz., and an insertion loss of -26 db. at

10 Hz. Furthermore, the phase shift approaches zero over a frequency range from 0.1 to 100 Hz.

Since the operation of the differentiator 20 can optionally be expressed as

$$e_o=Ke_i$$

and is not restricted to $e_o=e_i$, the arrangement of FIG. 2 may be extended as shown in FIG. 3 of the drawings by the provision of a further amplifier A_6 , capacitor C_4 and resistor R_{13} incorporated into the two paths respectively containing the amplifiers A_2 and A_3 . In this circuit of FIG. 3, K becomes

$$1/RwC,$$

and when such a differentiator is followed by the integrator 22, the filter has the output characteristic

$$E_o=(1/RwC)^2 E_i$$

and possesses essentially zero phase shift.

I claim:

1. An electrical filter designed to pass with essentially zero phase shift an input signal varying over a frequency band up to approximately 10 octaves, said filter comprising:

20 a differentiating network receiving at least a portion of said input signal;
an integrator receiving the output of said differentiating network; and
means for dynamically bounding the output of said differentiating network as a continuous function of variations in said input signal, so that the level of the data received by said integrator does not exceed the level of the data represented by the input signal variations.

2. An electrical filter according to claim 1 in which the 30 means for dynamically bounding the output of said differentiating network includes a pair of half-wave rectifiers respectively forming part of two signal paths each of which is connected in essentially parallel relationship with said differentiating network and each of which receives a portion of said input signal.

3. An electrical filter according to claim 2 in which each of the two signal paths which includes one of said pair of half-wave rectifiers also includes a parallel diode-resistor combination shunting the particular half-wave rectifier included in that 40 path.

4. An electrical filter according to claim 3, further including an amplifier, a series resistor R , and a capacitor C shunting said amplifier, all of such further components forming a common part of each of said two signal paths, whereby the output 45 characteristic E_o of the filter becomes $(1/RwC)^2 E_i$ where E_i is the input signal to said differentiating network.
